AIR CLEANER

Victor R. Abrams, Rockford, Ill.

Application September 19, 1944, Serial No. 554,829

8 Claims. (Cl. 183—75)

(Granted under the act of March 3, 1883, as
amended April 30, 1928; 370 O. G. 757)

The invention described herein may be manufactured and used by or for the Government for governmental purposes, without the payment to me of any royalty thereon.

The present invention pertains to a novel cleaner for the purpose of extracting entrained particles from a fluid stream and is a further development of an earlier invention shown in my co-pending application, Serial No. 526,625, filed March 15, 1944. The earlier invention consists of an apparatus wherein a portion of the main stream is diverted by reduced pressure, the diverted stream losing its particles by reason of their momentum. The diverted portion is caused to depart from the main stream through openings in the apparatus. These openings are preferably louvered to prevent accumulation of the separated particles within the apparatus and also to guide the diverted portion. It has been found that an accumulation of particles builds up on the louvers and is eventually picked up by the subsequent diverted stream portions.

The object of this invention is to provide an apparatus operating on the same basic principle and constructed in a manner to avoid such accumulation. In at least one embodiment of the invention, this object is accomplished by forming a venturi within the apparatus and extending a conduit from the throat of the venturi to the region where the separation of the particles occurs. The conduit is so mounted that the reduced pressure therein attracts the separated particles and returns them to the main stream, while the cleansed diverted portion is permitted to proceed to the point of use. In another form of the invention, the conduit is in the nature of a nozzle extended to the aforementioned louvers and positioned to sweep the louvers continuously by suction.

An illustrative embodiment of the invention is disclosed in the following description and in the accompanying drawings in which:

Figure 1 is a longitudinal sectional view of an air cleaner in accordance with the present invention;

Figure 2 is a longitudinal sectional view of a modification;

Figure 3 is a cross section, partly broken away, on the plane indicated by the line 3—3 of Figure 2;

Figure 4 is a longitudinal sectional view of another modification, and

Figure 5 is a reduced detail view of an end partition.

The simplest form of the invention is shown in

Figure 1. In this case the device includes a hollow airfoil 1 mounted lengthwise in the stream. The leading edge 2 is closed, and the trailing edge is formed with an opening 3. The dimension of the airfoil across the stream is determined according to the requirements of the particular apparatus.

The wall of the airfoil is formed with an opening 4 at a suitable point, and from this opening is extended a conduit 5 leading to a relatively low pressure source such as the intake manifold of an internal combustion engine. The reduced pressure causes a portion of the main stream to be deflected from its normal course and drawn into the opening 3 and to the port 4 and conduit 5. This portion, which is a small fraction of the entire stream, has been freed of its particles which, by reason of their momentum, have resisted the deflecting force and have continued in their normal direction.

The embodiment shown in Figures 2 and 3 is a hollow body 10 of rectangular cross section disposed in the stream and having both its leading edge 11 and its trailing edge 12 fully open. The dimension of the body transversely of the stream is determined according to the requirements of the apparatus. A pair of plates 12' are directed inward from opposite edges of the opening 11 convergently into the body 10, forming a throat or restriction 13 intermediate the opposite ends of the body. From the throat 13, the plates are continued divergently at 14 into contact with opposite edges of the opening 12. The angle between the plates 12' is 25 degrees or less and between the plates 14 about 21 degrees. The latter angle is divided by a pair of vanes 15 into three angles of approximately 7 degrees each. It is known in the art that the most efficient angular relation for Venturi action is an angle of about 25 degrees at the incident side and an angle of about 7 degrees on the emergent side of the throat.

Somewhat downstream from the throat 13, the sides of the body 10 are formed with substantial openings forming admission ports 16 through which fluid may be withdrawn from the encompassing stream in a direction transversely of the direction of fluid flow in said stream. Nozzles 17 are directed from the throat towards these openings and terminate short of the openings. The space between each nozzle and the adjacent opening 16 is bridged by a baffle 18 extending from the tip of the nozzle, on the down stream side, to the trailing edge of the corresponding opening. These baffles, together with the nozzles and the

plates 10, form chambers 19 at opposite sides of the throat 13. The chambers are brought into communication with one another at the ends of the body by a passage 20 formed at the corresponding end and defined by end wall 24 and partition 21 set against the edges of the members 12', 14, 15, 17 and 18.

The wall of the body 10 is formed with an opening 22 at the chamber 19, and from this opening a conduit 23 is extended to the point of use, such as the intake manifold of an internal combustion engine, in which there exists a pressure less than that of the stream outside the body 10. The reduced pressure diverts a relatively small portion of the main stream into the openings 16 and to the conduit 23. In being so deflected, the diverted portion is freed of a large percentage of entrained particles by the phenomenon described in connection with Figure 1.

The diverted stream tends to deposit particles on the baffles 18, as a result of the change of direction in flowing towards the reduced pressure opening 22. If the deposit is permitted to accumulate, it will eventually be swept by the diverted stream, and the efficiency of the separating action will be correspondingly reduced.

The stream of fluid flowing through the venturi formed by the plates 12' and 14 undergoes a reduction of pressure at the throat 13 in accordance with well known principles. An aspirator effect is thereby produced in the nozzles 17, whereby the deposit is drawn off the baffles 18 and delivered to the stream flowing through the venturi.

In the modification shown in Figure 4, the body 30 has opposed walls 31 of airfoil form on the external side. Adjacent to these walls, on the inward side, are oppositely curved airfoil walls 32 forming a venturi 33 designed to lie lengthwise in the stream. The ends of the walls 32 are spaced at 34 from the ends of the corresponding walls 31 on the down stream end, the openings 34 lying in a plane perpendicular to the axis of the venturi and forming admission ports through which fluid may be withdrawn from the passing fluid stream in a direction transversely of the direction of fluid flow therein. The venturi is of equal width at both ends in conformity with accepted Venturi design.

From each space or part 34 there extends a conduit 35 to the throat 36 of the venturi. The end of each conduit within the corresponding space 34 is spaced from the edges of that opening.

The chambers 37 formed by each wall 31 and the adjacent wall 32 are interconnected by any suitable construction, such as that shown in Figures 2 and 3, to form in effect a single chamber. An exhaust conduit 38 extends from the communicating chambers 37 to a low pressure source such as the intake manifold of an internal combustion engine, where the cleansed portion of the stream is to be used.

In the operation of this device, the low pressure within the chamber 37 causes a portion of the main stream to be diverted into the open ends 34. This portion is substantially free of particles by virtue of the change of direction which has caused the particles to continue in the original path. Whatever particles remain in the diverted stream are, for the most part, separated centrifugally from it towards the exposed ends of the conduits 35. There is a reduction of pressure in the conduits by reason of their communication with the throat 36 of the venturi, so that the particles thrown towards the conduit

are drawn therethrough and discharged into the throat 36 and into the main stream.

The several devices disclosed herein are distinguished from whirling or centrifugal separators in that they do not grind the solid particles. A centrifugal separator used as a pre-cleaner in conjunction with an oil-bath has been found to reduce the efficiency of the oil-bath by reason of the reduction in the size of the particles. The devices of this invention used in conjunction with an oil-bath, do not decrease the efficiency of the latter.

While specific embodiments of the invention have been shown and been described, it will be understood that various alterations may be made without departure from the spirit of the invention as indicated by the appended claims.

What I claim is:

1. A separator for removing particles from a fluid stream comprising an elongated hollow body adapted to be positioned lengthwise in a fluid stream, a venturi therein cooperating with the wall of said body to form a chamber therebetween, the inner walls of said venturi having an airfoil form in longitudinal section, said wall having a port therein for the admission of fluid into said chamber, said chamber having an exhaust port, said venturi having an opening in the throat thereof establishing communication between the venturi and the chamber, and the outer walls of said body having an airfoil section in the same section.

2. A separator for removing particles from a fluid stream comprising an elongated hollow body adapted to be positioned lengthwise in a fluid stream, a venturi therein cooperating with the wall of said body to form a chamber therebetween, said chamber having an exhaust port and an open end at the emission end of said venturi, and a conduit having one end mounted in said open end and extending to the throat of said venturi.

3. A separator for removing particles from a fluid stream comprising a body, a venturi therein spaced from the wall of said body to form a chamber, said chamber having an exhaust port and an intake port adapted to receive by diversion a portion of the stream in which said body and venturi are mounted, whereby particles are separated from said portion by their momentum, and a conduit extending from the region of separation to the throat of said venturi.

4. A separator for removing particles from a fluid stream, comprising inner and outer walls forming a hollow body adapted to be positioned lengthwise in a fluid stream, said inner walls forming a venturi having a throat and cooperating with said outer walls to form a chamber therebetween, said chamber having an admission port positioned for withdrawing fluid from the fluid stream transversely of the direction of fluid flow therein, said chamber having an exhaust port, and means for withdrawing particles from the immediate proximity of said admission port into the throat of said venturi.

5. A separator for removing particles from a fluid stream, comprising inner and outer walls forming a hollow body adapted to be positioned lengthwise in a fluid stream, said inner walls forming a venturi having a throat and cooperating with said outer walls to form a chamber therebetween, said chamber having an admission port positioned for withdrawing fluid from the fluid stream transversely of the direction of fluid flow therein, said chamber having an exhaust port, a baffle extending from said admission port

into said chamber transversely of the direction of fluid flow in said stream, and means for withdrawing particles from said baffle and the immediate proximity of said admission port into the throat of said venturi.

6. A separator for removing particles from a fluid stream, comprising inner and outer walls forming a hollow body adapted to be positioned lengthwise in a fluid stream, said inner walls forming a venturi having a throat and cooperating with said outer walls to form a chamber therebetween, said chamber having an admission port positioned for withdrawing fluid from the fluid stream transversely of the direction of fluid flow therein, said chamber having exhaust port, a baffle extending from the down stream side of said admission port into said chamber toward the throat of said venturi at an acute angle to the direction of fluid flow in said stream, and means for withdrawing particles from said baffle and the immediate proximity of said admission port to the throat of said venturi.

7. A separator for removing particles from a fluid stream, comprising inner and outer walls forming a hollow body adapted to be positioned lengthwise in a fluid stream, said inner walls forming a venturi having a throat and cooperating with said outer walls to form a chamber there-

between, said chamber having an admission port positioned for withdrawing fluid from the fluid stream transversely of the direction of fluid flow therein, said chamber having an exhaust port, a baffle extending from the down stream side of said admission port into said chamber toward the throat of said venturi at an acute angle to the direction of fluid flow in said stream, and a nozzle extending from the throat of said venturi to the side of said baffle facing toward the exhaust port.

8. A separator for removing particles from a fluid stream, comprising inner and outer walls forming a hollow body adapted to be positioned lengthwise in a fluid stream, said inner walls forming a venturi having a throat and cooperating with said outer walls to form a chamber therebetween, said chamber having an admission port positioned for withdrawing fluid from the fluid stream transversely of the direction of fluid flow therein, said chamber having an exhaust port, means for withdrawing particles from the immediate proximity of said admission port into the throat of said venturi, and partitions in said venturi on the emission side of said throat dividing the venturi into longitudinally extending passages.
